UNITED STATES PATENT OFFICE.

MATTHEW H. BROOKSBANK, OF WEST BERGEN, NEW JERSEY.

LIQUID-FUEL BURNER.

SPECIFICATION forming part of Letters Patent No. 448,407, dated March 17, 1891.

Application filed April 28, 1890. Serial No. 349,773. (No model.)

To all whom it may concern:

Be it known that I, MATTHEW H. BROOKSBANK, a citizen of the United States, residing at West Bergen, Hudson county, New Jersey, have invented certain new and useful Improvements in Liquid-Fuel Burners, fully described and represented in the following specification and the accompanying drawings, forming a part of the same.

10 The object of this invention is to furnish a means of diffusing the oil effectively within the current of an air-blast, so as to promote its subsequent combustion; and the invention consists partly in the combination, with a blast-conduit, of a propeller-wheel and a revolving distributor actuated by the same, and partly in details of construction hereinafter described and claimed.

20 The drawings show a burner having the blast-conduit passed through the same, Figure 1 showing the inlet end of the burner; Fig. 2, the upper side of the same provided with the feed-pipe. Fig. 3 is a plan partly in section where hatched on line $z-z$ in Fig. 4, 25 which latter figure is a longitudinal section through the center of the burner. Fig. 5 is a longitudinal section on line xx in Figs. 3 and 4; and Fig. 6 is a longitudinal section on line $x'x'$ in Fig. 4, looking toward the oil-inlets.

30 The burner is shown as a square box a , divided longitudinally into chambers a' and b' by a horizontal partition b . An inlet-nozzle c is fixed to one end of the box, from which the blast passes into both the chambers toward the mouth c' . A propeller or motor-wheel d is mounted upon a vertical spindle in the chamber b' , and the blast from the nozzle c is directed toward one side of the wheel by a deflector e , thus rotating the wheel, as 35 shown by the arrow e' in Fig. 5. A steam-jet may also be used to rotate the propeller. An oil-pipe f is applied to the top of the box to supply the oil to a series of oil-holes g , which enter the upper side of the chamber a 40 in proximity to a rotating distributor. Such distributor is shown in Fig. 6 formed of a round axle h , having a number of wires i inserted transversely to form radial arms; but the arms are shown flat in Fig. 4. The lower 45 end of the axle h is formed with a square hole and fitted upon the upper end of the pro-

peller-spindle d' , which is squared to fit the same, and the upper end of the axle is journaled in the bottom of an oil-pocket k , in the under side of which the holes g are formed. 55

For convenience of construction the oil-pipe f is tapped into a lug l upon the top of the casting, within which a passage m communicates by a hole n with the oil-pocket k . A screw o is inserted in the top of the lug l in 60 line with the hole n for the purpose of cleaning the same when clogged, and a screw o' is inserted in the end of the lug l to clean the passage m .

To facilitate the introduction of the distributor and propeller-wheel within the box, the partition b is made removable and secured therein by a screw p , and the lower end of the propeller-spindle is formed with a recess, in which a screw q is inserted through the side 70 of the box.

The oil-pocket k is detachable from within the box and held therein by screws k' , inserted through the upper side of the box, and the removal of the screws p , q , and k' permits the 75 withdrawal of the partition with the propeller, distributor, and oil-pocket.

The lateral walls of the chamber a' are provided with longitudinal grooves forming ledges r , such ledges being shown in detachable plates r' , secured within the box by screws s , as shown in Fig. 3.

The end of the partition b at the mouth of the burner is tapered toward the chamber a' , and a deflector t is secured within the chamber b' to direct the air passing through such chamber upward into contact with the air discharged from the burner, as indicated by the arrow u' in Fig. 4.

The operation of the device is as follows: 90 A regulated supply of oil is fed through the pipe f and enters the oil-pocket k , from whence it is discharged through the holes g downward upon the arms i of the distributor. The blast passing through the chambers a' and b' rotates the propeller d and the distributor, and thus causes the arms of the distributor to diffuse the oil in the blast of air passing through the chamber a' . The oil thrown by the distributor against the side walls of the chamber a' is caught by the ledges r and prevented 95 from running downward, while the force of the 100

- blast drives the oil forward upon such ledges, and thus discharges it from the mouth c' of the burner at the point indicated by the arrow u in Fig. 4. Any oil falling upon the partition b is driven by the blast toward the mouth of the burner, where the blast from the chamber b' is thrown upward by the deflector t , and thus throws such oil into the main blast from the chamber a' .
- 10 With a motor-wheel arranged upon one side of the partition b and connected with a distributor upon the opposite side it is obviously immaterial what means be used to rotate the motor-wheel.
- 15 A pipe v , having its nozzle directed toward the blades of the motor-wheel, is shown in dotted lines in Fig. 5 to indicate that steam may be used, if desired.
- My invention differs from other hydrocarbon-burners in having the distributor and a separate propeller-wheel mounted upon an axle or spindle transverse to the blast-chamber, and thus at right angles to the direction of the blast.
- 25 Having thus set forth the invention, what I claim herein is—
1. A liquid-fuel burner having a spindle or axle projected across the blast-chamber, a rotary distributor affixed to such axle, and a separate motor-wheel attached to the axle and propelled by a blast to rotate such distributor, as and for the purpose set forth.
  2. A liquid-fuel burner divided longitudinally into two chambers and provided with a nozzle for directing the blast into such chambers, a rotary distributor in one chamber and a motor-wheel in the other chamber connected with the rotary distributor to actuate the same, and an oil-supply pipe connected with the chamber having the rotary distributor, substantially as herein set forth.
  3. A liquid-fuel burner divided longitudinally by a horizontal partition into an upper chamber a , provided with an oil-inlet in its upper side, and lower chamber b' , and provided with a rotary distributor in the upper chamber below the oil-inlet, a motor-wheel in the chamber b' , with connection to the rotary distributor, a nozzle c , to direct the blast into both chambers, the deflector e , directing the blast upon the motor-wheel, and the deflector t , to direct the air upward from the outlet of the chamber b' , as and for the purpose set forth.
  4. A liquid-fuel burner consisting in the box a , divided into upper and lower chambers, with the longitudinal ledges r formed in the sides of the upper chamber, the rotary distributor in the upper chamber, the motor-wheel in the lower chamber in connection

with the rotary distributor, an oil-supply pipe connected with the upper chamber, and a nozzle for directing the blast into both the chambers, as and for the purpose set forth.

5. A liquid-fuel burner consisting in the box a , divided into upper and lower chambers, with the longitudinal ledges r formed in the sides of the upper chamber, the rotary distributor in the upper chamber, the motor-wheel in the lower chamber in connection with the rotary distributor, a nozzle for directing the blast into both the chambers, a detachable oil-pocket in the top of the upper chamber with the upper pivot of the distributor journaled therein and having discharge-holes in its lower side adjacent to such pivot, and an oil-pipe connected with such oil-pocket, as and for the purpose set forth.

6. A liquid-fuel burner consisting of the box a , divided into upper and lower chambers, with the longitudinal ledges r formed in the sides of the upper chamber, the rotary distributor in the upper chamber, the motor-wheel in the lower chamber in connection with the rotary distributor, a nozzle for directing the blast into both the chambers, a detachable oil-pocket in the top of the upper chamber with the upper pivot of the distributor journaled therein and having discharge-holes in its lower side adjacent to such pivot, the lug l upon the top of the box, provided with oil-pipe f and passage m , communicating by hole n with the oil-pocket, and the screw o in the top of the lug l for cleaning the hole n when clogged, substantially as herein set forth.

7. A liquid-fuel burner consisting of the box a , divided into chambers a' and b' by detachable partition b , having deflector t formed thereon, the propeller d , pivoted in the chamber b' and detachable with the partition, with squared axle projected through the partition, the oil-pocket k , secured detachably within the chamber a' by screws k' and provided with an oil-inlet n and discharge-holes g , the distributor having its upper pivot supported in the oil-pocket and its lower end upon the propeller-axle, the deflector t at the outlet end of the chamber b' , and the nozzle c for directing the blast into both chambers, the whole arranged and operated substantially as herein set forth.

In testimony whereof I have hereunto set my hand in the presence of two subscribing witnesses.

MATTHEW H. BROOKSBANK.
